UNITED STATES PATENT OFFICE

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY

BLOWER VALVE FOR ROCK DRILLS

Application filed May 5, 1930. Serial No. 449,797.

This invention relates to rock drills, but more particularly to blowing valves for a rock drill.

It is an object of this invention to enable the operator of a rock drill to quickly and economically blow the dust and rock cutting from the drill hole by a slight pressure on a projecting stem of the blower valve.

Another object of the invention is to enable the economical construction of a valve which will permit the cleansing of the drill hole by compressed air. These objects are accomplished by the mechanism shown in the accompanying drawing.

15 The drawing is a sectional elevation of so much of a rock drill as will serve to make clear the invention.

Referring more particularly to the drawing, 2 designates the cylinder of a rock drill 20 within which a piston 4 is adapted to reciprocate and to deliver hammer blows to a working implement 6. A rifle bar 8 attached to the pawl and ratchet mechanism 10 serves to cause the rotation of the drill steel 6 through the medium of the rifle nut 12 and the chuck mechanism 14. The rotation mechanism and the general operation of the drill has not been completely explained since it forms no part of this invention. Those skilled 30 in the art and those interested in blower valves are familiar with the operation of rock drills.

The compressed air required to operate the piston of the rock drill is admitted at the inlet 16 which is controlled by a throttle valve 18. A distributing valve 20 of the oscillating type operates in a valve chamber 22. In the present instance as illustrated by the drawing the right hand end of the operating valve is raised from the seat and compressed air passes over the right hand end of the valve through the passageways 24, 26 and 28 into the right hand end of the rock drill cylinder. When the piston 4 has nearly completed its movement to the left the right hand end of the valve 20 is closed due to the flow of air over that end and the left hand end of the valve 20 is raised admitting air to the left of the piston 4 for the return stroke. The annular groove 30 assists in exhausting pressure fluid from both the right hand end of the cylinder and

the left hand end of the cylinder, the pressure fluid having once been used is discharged to the atmosphere through the exhaust port 32.

Frequently during the operation of a rock drill the hole being drilled becomes clogged with fine rock dust and cuttings from the rock being drilled. If water is being used to cleanse the hole, the dust and cuttings form a sludge with the water. In either case it is necessary to remove the dust and chips or the sludge at frequent intervals by a strong blast of compressed air to the bottom of the drill hole. To this end the blower valve about to be described is attached to the rock drill. Underneath the distribution valve 20 in the boss 36 an aperture 34 is drilled. This aperture passes through the inlet passage 28, the exhaust passage 32 and the inlet passage 29. The valve itself is formed of a piece of bar stock reduced to a stem by turning at the points 38, 39, 40 and 42. Turning at the points mentioned forms heads 44, 46, 48 and 50 on the valve stem. An aperture 52 is formed in the back head 54 of the rock drill.

The assembly of the blower valve is as follows: Before the back head 54 of the rock drill is put in place, the valve stem 39 is placed in the aperture 34 and button 56 fitted to the valve stem 39 a spring 58 is placed in the hollow 60 of the head 50 the back head 54 is then put in place on the rock drill, the spring 58 being in place in the aperture 52.

Assuming that the operator wishes to stop drilling operations and to blow the hole clear of accumulated dust and cuttings the operation of the blower valve is as follows:

The operator pushes the button 56 rearwardly, this causes the head 48 to move rearwardly closing the inlet passages 26 and 28. At the same time the head 46 closes the passage 62 thus preventing the exhaust of air at the port 32. The inlet passage 29 remains open and air flows through the passage 29 into the left hand end of the cylinder 2.

The right hand end of the operating valve 20 will remain closed due to the fact that a passage 64 is opened when the blower valve is forced rearwardly. This permits air to flow freely over the right hand end of the

valve 20 for an instant and the valve is thus quickly closed due to the differential in pressure on top of the valve and underneath the valve. The differential referred to will always be greater than the differential in pressure above the left hand end of the valve 20 and under that end of the valve because pressure fluid admitted into the left hand end of the cylinder 2 during the blowing operation is not exhausted quite as rapidly as it may enter and therefore the pressures above the valve and below the valve are substantially equal.

Compressed air which enters through the passage 29 during the blowing operation first fills the left hand end of the cylinder 2 and then forces air down the flutes 66 in the nose 68 of the piston 4 after which it passes through the hollow drill steel 6 between the water tube 70 and the walls of the aperture in the drill steel. In this manner compressed air is made to enter the drill hole at a high velocity forcing water, sludge, dust and chips from the hole, thus effectively cleansing it. When the drilled hole has been satisfactorily cleansed the operator releases the button 56 and the spring 58 forces the blower valve back to the position shown in the figure, the head 44 acting as a stop to limit the forward movement of the valve.

I claim:

1. In a fluid actuated rock drill of the hammer type, the combination of a cylinder and a reciprocating piston, a valve chest and distributing valve therein controlling the supply of pressure fluid for the cylinder inlet passages between the valve chest and the cylinder for supplying pressure fluid for actuating the piston, an exhaust port in the cylinder for exhausting spent pressure fluid from both ends of the cylinder, means for closing one of said inlet passages and the exhaust port thus permitting pressure fluid to enter one end of the cylinder and to flow from that end to the drilled hole, said means comprising a valve stem having a plurality of heads thereon, said heads adapted to cooperate with a bore in the cylinder wall, said bore crossing the inlet passages and the exhaust passage.

2. In a fluid actuated rock drill of the hammer type, the combination of a cylinder and a reciprocating piston, a back head on said cylinder, a valve chest and distributing valve therein controlling the supply of pressure fluid for the cylinder inlet passages between the valve chest and the cylinder for supplying pressure fluid for actuating the piston, an exhaust port in the cylinder for exhausting spent pressure fluid from both ends of the cylinder, means for closing one of said inlet passages and the exhaust port thus permitting pressure fluid to enter one end of the cylinder and to flow from that end to the drilled hole, said means comprising a valve

stem having a plurality of heads thereon, said heads adapted to cooperate with a bore in the cylinder wall, said bore crossing the inlet passages and the exhaust passage, an aperture in the back head and resilient means in said aperture normally holding the blower valve in its inoperative position.

3. In a fluid actuated rock drill of the hammer type, the combination of a cylinder and a reciprocating piston, a valve chest and a distributing valve therein controlling the supply of pressure fluid for the cylinder, inlet passages between the valve chest and the cylinder, an exhaust port in the cylinder, means for closing off one of said supply passages from the cylinder and of closing said exhaust port to the atmosphere, said means opening a direct passage between the said supply passage and the atmosphere and permitting an uninterrupted supply of pressure fluid to flow from the other supply passage into the front end of the cylinder and thence to the hollow drill steel.

4. In a fluid actuated rock drill of the hammer type, the combination of a cylinder and a reciprocating piston, a valve chest and a distributing valve therein controlling the supply of pressure fluid for the cylinder, inlet passages between the valve chest and the cylinder, an exhaust port in the cylinder, means for closing off one of said supply passages from the cylinder and of closing said exhaust port to the atmosphere, said means opening a direct passage between the said supply passage and the atmosphere and permitting an uninterrupted supply of pressure fluid to flow from the other supply passage into the front end of the cylinder and thence to the hollow drill steel, said means comprising a valve in a bore in the cylinder, said valve having a plurality of heads, one of said heads acting as a stop to limit the forward movement of the valve, another of the heads acting as a throttle valve to close one of the supply passages, a head intermediate those two heads for closing the exhaust passage and a fourth head adapted to close a passage-way leading from one of the supply passages to the atmosphere when the blower valve is not in operation.

In testimony whereof I have signed this specification.

EARL B. LEAR.
